UNITED STATES PATENT OFFICE.

HARRY D. CLINTON, OF JOHNSON CITY, NEW YORK.

SPOOL AND BOBBIN.

Application filed September 13, 1927. Serial No. 219,301.

This invention relates to spools and bobbins and aims to provide an improved construction thereof.

The principal object is to produce spools and bobbins of durable and non-breakable character adapted to withstand the rough use to which they are subjected in textile mills in the various operations of loading and feeding yarn or silk for cloth and fabric weaving.

The invention will be best understood by reference to the accompanying drawings illustrating one embodiment thereof.

In said drawings:

Fig. 1 is a perspective view illustrating a spool with head, bushing and plug at one end in applicative relation to the barrel, the parts being shown in transverse section;

Fig. 2 is a sectional elevation representing a finished spool, the united parts at one end being shown in transverse section;

Fig. 3 is an enlarged perspective view of one form of bushing; and

Fig. 4 is a similar view of a modified form of bushing.

Referring to the drawings, 5 denotes the wooden barrel or stave of a spool or bobbin. Said barrel is shown bored and counterbored to provide a central enlarged recess 5^a with marginal ledge or shoulder 5^b in its end.

In this instance, said recess and the counter-bore to said ledge are annular, the recess being tapered at its bottom toward the central bore of the barrel and said ledge being formed at slight depth from the end of the barrel. In some instances it may be desirable to make either or both the recess and counter-bore to the ledge polygonal rather than annular in form, but in such cases the form of plug and/or bushing hereinafter described, must be correspondingly modified as will become obvious.

The heads 6 to be applied at the ends of the barrel formed as described, are of hard vulcanized fibre or other composition resisting breakage. Such heads are cut or punched from slabs of the component material and are stamped, pressed and trimmed to desired form having central apertures 6^a of a shape and diameter corresponding with the counter-bore or inner edge of the barrel wall at its ends.

In the various types of spools made, the heads are substantially the same, any modification or variance in the form thereof be-

ing in respect more particularly to their thickness, the shape and diameter of their central apertures and the trim of their outer peripheries. However, for reasons which will hereinafter appear, it may be desirable 60 in some instances to serrate the heads around the margins of their central apertures on the inner faces thereof for an extent equal substantially to the thickness of the extended wall portion of the barrel against which 65 they are placed, such serrations being made deepest at said margins and terminative along the line where the outer edge of the barrel wall meets the heads.

In the illustrative embodiment the hard 70 composition heads are shown secured to the spool barrel by means of fastening plugs 7 fitted into the ends of the spool barrel in cooperation with bushings or liners 8 engaging over a portion of the heads and under a portion of the plugs.

Said plugs are formed with shank and enlarged head portions 7^a and 7^b respectively conforming with the aforesaid central recess and counter-bore of the barrel 80 so as to fit tightly thereto. In this instance they are of annular form having central bores and tapering heads terminating with a shoulder 7^c opposing the marginal ledge 5^b in the end of the barrel. As these 85 plugs are subjected to compression strains, they are formed preferably of dog-wood which is hard and not easily cracked or split, although other material may be equally suitable.

Said bushings or liners are formed to fit within the counter-bore of the barrel end with a portion thereof resting upon the aforesaid ledge 5^b and another portion engaging over the head around the margin 95 of the central aperture therein. In this instance the bushings embody metallic rings or sleeves having marginal flanges 8^a and 8^b at opposite ends thereof extending outwardly and inwardly respectively so that their walls are substantially Z-shape in cross-section. Portions of these bushings are serrated for the purpose of impregnating or engaging in the spool head and plug, and in some instances into the spool barrel also. 100 105

In Fig. 3 one embodiment of the bushing is shown, wherein only the flange portions thereof are serrated, the upper flange being serrated on its under side and the lower flange being serrated on its upper side. In 110

this embodiment the bushing will engage in the spool head and plug only, its body being merely pressed against the inner wall of the barrel.

5 In Fig. 4 another embodiment or modification of the bushing is shown, wherein the wall or body portion thereof also is serrated, the serrations being of a somewhat different character. In this embodiment the 10 bushing will engage in the end of the spool barrel in addition to the head and plug, thus assuring a stronger union of the parts.

In some instances it may be desirable to 15 form these bushings or liners from metal having expansive qualities permitting them to spread or expand outwardly so as to engage deeper into the end of the spool barrel under the wedging force of the plug heads compressed therein. In some instances they 20 may also be made frusto-conical or with walls tapering slightly toward their inwardly flanged ends to facilitate their insertion in the spool heads and barrel ends and to permit a greater expansion under action 25 of the plugs.

In applying a head to a spool barrel, the head is placed against the end of the barrel with its central aperture registering with the counter-bore in the latter. One of the 30 described bushings is then inserted through the central aperture of the head with its outwardly extended flange overlying the outer face of the head along the edge of said aperture and its inwardly extended flange 35 resting upon the ledge 5^b in the barrel end. One of the fastening plugs which is advantageously coated with glue or cement, is then inserted through said bushing and pressed into place with its shank portion 7^a fitting 40 into the recess 5^a of the barrel and its tapering head portion 7^b compressed within the bushing, thereby pressing and in some instances also expanding the latter against the wall of the barrel. The pressure applied in 45 thus wedging the fastener plug into place forces the bushing downwardly so that the serrations in the under side of its outer flange will embed or engage in the spool head around the central aperture therein, 50 while the serrations in the upper side of its lower flange will embed or engage in the shoulder portion 7^c of the plug. This applicative pressure may be continued until the 55 outwardly extended flange 8^a of the bushing lies flush with the surface of the spool head on the outer face of the latter as represented in Fig. 2.

When bushings or liners having serrations in their wall or body portions in addition to 60 their peripheral flanges are used, they will embed or engage also in those parts of the spool barrel and plug against which they are pressed or wedged in the manner described.

Being so forced with its head-portion 65 wedged within and down upon the bushing

and its glue-coated shank or body portion fitted into the recess 5^a of the barrel, the fastener plug together with said bushing which engages over the spool head, positively secures said head to the barrel. By reason 70 of its firm embedment or engagement in the outer face of the spool head and in the shouldered portion of the plug which holds it in place, the bushing member not only prevents removal of the spool head but also 75 prevents its rotation or slippage in relation to the barrel.

Upon completing a spool in the manner described, the fastening plug is "trimmed-off" and the spool is finally finished and 80 polished, whereupon it will have the appearance represented by the lower portion of Fig. 2.

So firmly is the spool head thus secured to 85 the barrel that when the glue or cement on the plug has dried, the parts cannot be again separated. Any abnormal force applied to remove the head from the barrel will simply break the head or split the barrel and plug before allowing any separation of the parts. 90 A strong, durable and substantially non-breakable spool of light construction is thus produced.

Obviously, variations in the form of 95 barrel-end, spool-head, fastening plug and bushing may be made without departing from the spirit and scope of the invention. Therefore it is not intended that the invention shall be limited by the appended claims to the specific construction shown and described. 100

Having thus described my invention, what I claim is new and desire to secure by Letters Patent of the United States is:

1. A spool or bobbin comprising a wooden 105 barrel having a central shouldered recess in each end, hard composition heads faced against the ends of the barrel and having central apertures registering with the shouldered recess therein, thin metallic bushings 110 extending through said heads and into the barrel ends and having serrated marginal flanges extending oppositely from opposite ends thereof with their outward extending flanges over-engaging the apertured edges of 115 the heads and their inward extending flanges pressing against the shouldered portions of the barrel, and wooden plugs at each end of the barrel having enlarged tapering head-portions compressed into said bushings to 120 expand the latter outwardly against the barrel walls and shank-portions fitting into the recesses of the barrel, said plug being driven into place by the application of endwise force. 125

2. In a spool or bobbin, means for securing a hard composition head to a wooden barrel comprising a metallic expandible bushing and cooperating wooden plug extended through an aperture of the head into the 130

receptive end of the barrel in wedged engagement with the latter, said bushing being formed with serrated marginal flanges extending oppositely from opposite ends thereof and having its outward extending flange engaging over the head while its inward extending flange is pressed against an abutment in the barrel end, and said plug being formed with a tapering head-portion compressed by 10 endwise pressure into said bushing to expand the latter and with an extended shank-portion thereof retained within a recess in the end of the barrel.

3. In a spool or bobbin embodying a wooden barrel and hard composition heads together with wooden fastening plugs; means cooperating with said plugs to secure the heads to the ends of the barrel, comprising metallic bushings having marginal flanges extending from opposite ends in opposite directions serrated on oppositely related surfaces, said bushings being inserted through central apertures in said heads and into the ends of said barrel with their outward extending flanges over-extending and engaging in portions of the heads and with their inward extending flanges underlying and engaging in portions of said plugs which are driven endwise into the barrel 25 with enlarged portions thereof compressing into the bushings and forcing the latter against abutment portions of the barrel, whereby the heads are clamped and held firmly to the ends of the barrel.

35 4. In a spool or bobbin, means for applying a hard composition head to a wooden barrel, comprising an expansible metallic bushing insertable through the head and partially into the recessed end of the barrel with a portion thereof overextending a portion of the head, and a plug having shank and enlarged tapering head portions driven into the barrel end with its head portion compressed into said bushing to expand the latter engageably against the wall of the barrel and its shank portion fitting into the body of the barrel for holding it firmly in place, a portion of said bushing being engaged under and in the plug between the shank and compressed head portions thereof.

5. In a spool or bobbin embodying a wooden barrel and hard composition heads, together with wooden fastening plugs, means cooperating with said plugs for securing the heads to the ends of the barrel, comprising serrated expansible metal bushings having portions thereof overextending portions of the heads and other portions underlying portions of said plugs which are driven lengthwise into the barrel ends with enlarged portions thereof compressing into

said bushings so as to expand and wedge the latter against removal from the barrel.

6. A spool or bobbin embodying a wooden barrel and hard composition heads, together with wooden end plugs, wherein the heads are secured on the ends of the barrel by expansible means engaging over and into portions of the heads and under and into portions of the plugs, which latter are driven into the ends of the barrel with portions thereof compressing into and expanding said means against the end-walls of the barrel so as to hold the same therein against 75 rotation and removal.

7. In a spool or bobbin embodying a wooden barrel and hard composition heads, together with wooden fastening plugs, means cooperating with said plugs for securing the heads positively to the barrel, said means comprising thin metallic bushings having serrated marginal flanges at opposite ends thereof respectively overextending portions of the heads and underlying portions of the plugs, which latter are driven into the ends of the barrel with enlarged portions thereof compressing into said bushings and with shank portions thereof fitting into recesses in the barrel body for wedging 90 and holding said bushings against and within the walls of the barrel to prevent removal and displacement therefrom.

8. A spool or bobbin comprising a wooden barrel having a shouldered recess in each end; hard composition heads faced against the ends of the barrel and having central apertures registering with the shouldered recess therein; metallic bushings extending through said heads and into the barrel ends 100 having marginal flanges extending outwardly and inwardly respectively from opposite ends thereof, the outward extending flanges being serrated along their under surfaces and over-engaging the aperture edges of the heads and the inward extending flanges being serrated along their upper surfaces and adapted to abut the shouldered portions of the barrel; together with wooden plugs at each end of the barrel having enlarged head-portions tapering to shoulders from which shank-portions thereof extend, said plugs being driven endwise into the barrel with their head-portions compressing into said bushings, their shank-portions extending and fitting into the recesses of the barrel and their shoulders depressing upon the inward extending flanges of the bushings, thereby wedging the latter tightly within the barrel to hold the heads in place 110 on its ends.

In testimony whereof I affix my signature.

HARRY D. CLINTON.
